MINING APPARATUS

Erskine Ramsay, Birmingham, Ala.

Application August 15, 1941, Serial No. 406,963

8 Claims. (Cl. 262—9)

This invention relates to apparatus for mining generally. In its more specific aspects, the invention is concerned with the mining of coal and in the driving of headings and air courses in a coal mine, but the invention is equally applicable to other mining operations, as well as to the mining of coal from a room or long wall.

One object of my invention is to provide apparatus for driving entries, headings and air courses which shall in a continuous operation mine the coal, advance into the working face, and remove the coal from the mine.

A further object of my invention is to provide mining apparatus which shall embody rotary cutting tools and means to advance the same continuously, together with means to oscillate the rotating tools through an arc defining the width of the heading or entry being mined.

Apparatus embodying features of my invention is illustrated in the accompanying drawings forming a part of this application, in which

Fig. 1 is a longitudinal sectional view taken vertically through the forward portion of the machine;

Fig. 2 is a sectional view taken substantially along the line II—II of Fig. 1;

Fig. 3 is a sectional plan view taken along the line III—III of Fig. 2;

Fig. 4 is a sectional view taken along the line IV—IV of Fig. 1;

Fig. 5 is a fragmental elevational view of the mechanism shown in Fig. 4, as viewed from the rear of the curved rack, with certain parts thereof in section;

Fig. 6 is a fragmentary view showing the means for adjusting the height of the machine in its work;

Fig. 7 is a view taken along the line VII—VII of Fig. 6;

Fig. 8 is a fragmental plan view of the rear of the machine with one-half of the view in section and showing the manner of the delivery of the coal from the machine to a supplementary conveyor;

Fig. 9 is a vertical sectional view of the rear of the machine showing the drive for the conveyors of the machine and their relation to the supplementary conveyor for taking the mined material from the machine out of the mine; and

Fig. 10 is a diagrammatic sectional view showing the manner of use of the machine in driving headings, entries and air courses.

Referring to the drawings, the machine comprises framework 11 which may be formed of castings and structural shapes, and is supported

on a pair of endless tracks 12 of the caterpillar type. Adjacent the rear of the tracks 12 is a roller 10 which acts as a support and prevents the machine from tipping on the tracks. Power for driving the tracks 12 is transmitted thereto through worms 13, and the rotation of the shafts which drive these worms is effected by means later to be described.

On either side of the machine is provided an 10 inturned channel 14 which forms a guide shoe adapted to bear against the sides of the heading, thus to insure that the machine travels in a straight line. Handwheels 16 fast on threaded stems 17 are provided at each end of the guide 15 shoes so that either end thereof selectively may be moved toward or from the side of the heading to exert a guiding force on the machine. The stems 17 are threaded into brackets 18 carried by the frame 11.

20 Secured to the framework is a transversely extending divided housing comprising portions 19 and 21 within which is rotatably mounted a shaft 22. Loosely mounted on this shaft is a gear 23 in mesh with a pinion 24 driven by a motor 26, both 25 of which gears may be enclosed in a housing 27 for the sake of safety. Integral with the gear is one element 28 of a clutch 30, the other element 29 being slidably splined to the shaft 22. The elements 28 and 29 may be engaged and disengaged by means of a pivoted yoke 31 and the lever arm 32. It will be apparent that when the members 28 and 29 are engaged, shaft 22 is driven by the motor 26 in a direction opposite that of the motor.

35 On the other end the shaft 22 has loosely mounted thereon a sprocket 33, which has connected thereto one member 34 of a clutch 35. The other member 36 of the clutch is slidably splined to the shaft 22, and the members 34 and 40 36 may be engaged and disengaged by means of a yoke 37 and lever 38. A sprocket 39 is directly connected to the motor shaft and is connected by a chain 41 to the sprocket 33, thus to drive the shaft 22 in the same direction as the motor when clutch 35 is engaged. A member 42 cross connects the clutch levers 32 and 37, thus to prevent engagement of both clutches at the same time.

45 The worms 13 are mounted on the shaft 22 and drive gears 43 keyed to forwardly extending shafts 44 which are mounted on opposite sides of the machine in suitable bearings 46, only assembly being shown in Fig. 3. The other side being similar, requires no detailed description. Each of the shafts is provided with a clutch 47 55 comprising one element 49 keyed to the shafts

and another element 48 slidably splined thereto. Pivoted yokes and levers 52 are adapted independently to engage and disengage the clutches 47.

The shafts 44 extend forwardly to a point just over the rear of the tracks 12, at which point they are provided with worms 53 in mesh with gears 54 which are keyed to transversely extending stub shafts 56. These latter shafts carry sprockets 57 in mesh with the tracks 12 for driving them in the manner well understood.

From the foregoing it will be seen that whenever the two clutches 47 are engaged and either of the clutches 30 or 35 is engaged, the tracks 12 will be driven. If clutch 30 is engaged, the drive will be from the motor 26 through the gear 23, and hence the machine will move forward. If clutch 35 is engaged, the driving power is transmitted to the tracks from motor 26 through the chain 41 and sprockets 33 and 39, and hence the machine moves rearwardly. Inasmuch as the ratio of reduction between the motor 26 and the shaft 22 through the gears 23 and 24 is much greater than the ratio of reduction through the sprockets 39 and 33 to the shaft 22, the machine will move rearwardly at a much greater rate than it will move forwardly. If it is desired to turn the machine, either of the tracks 12 may be stopped by disengaging either of the clutches 47.

Secured to the frame 11 is an upstanding housing 58 in which is mounted a large shaft 59. This shaft forms a post about which the cutter mechanism oscillates, as will now be described.

Supported for oscillation on the shaft 59 is a frame 61, and mounted on the frame are two electric motors 62 and 63, the shafts of which rotate in the direction of the arrows 64 and 66, respectively.

Secured to the frame 61 is an inclined shaft and gear housing 67 within which is rotatably mounted a shaft 68. This shaft has keyed thereto on two bevel gears 69 and 71 which are driven by pinions 72 and 73 mounted on the shafts of the motors 62 and 63, respectively.

At its upper end the shaft 68 is provided with a cutter 74 adapted to contact the roof of the heading and break the same, while a similar cutter 76 is provided on the lower end of the shaft for breaking the coal adjacent the floor line of the heading. Intermediate the upper and lower cutters 74 and 76 are provided a plurality of circular saws 77, supported on and driven by shafts 78, journaled in bearings 79, which may be formed as part of the housing 61. The shafts 78 are driven by bevel gears 81 and 82 from shaft 68. Whenever the motor 62 and 63 are rotating, all of the cutters and saws are likewise rotating. As will be seen in Figs. 1 and 10, the sides of the saws 77 are substantially parallel to the mine face being cut and their axes are normal to said face. The mechanism for oscillating the frame 61, and hence the cutters and saws, about the shaft 59, will now be described, referring particularly to Figs. 4 and 5.

Intermediate its ends, shaft 68 is provided with a worm 83 in mesh with a gear 84 on a transversely extending shaft 86. Shaft 86 has keyed thereto two pinions 87 and 88, while the gear 84 is slidably splined to the shaft 86. At either end the shaft 86 is provided with a pair of collars 89 between which fit yokes 91 and 92. The yokes are both secured to a member 93 which slides in a bearing 94 which also may be formed as a part of the housing 61. The pinions 87 and 88 are adapted selectively to engage a pair of

gears 96 and 97 mounted on shafts 98 and 99 in bearings 101 and 102. At their lower ends the shafts 98 and 99 carry pinions 103 and 104 in mesh with a curved rack 106 secured to the forward portion of the frame 11. Power is transmitted from the motors 62 and 63 through shaft 68, worm 83, gear 84, shaft 86, pinion 87 or 88, gear 96 or 97, shaft 101 or 102, pinion 103 or 104, to the rack 106, depending on which gear 87 or 88 is in mesh, thus resulting in oscillating the frame 61, motors 62 and 63, and the cutters and saws, about the upright post 59. It will be seen that this arc of oscillation defines the width of the cut being made by the machine.

Whenever the cutters and saws reach the extreme end of the swing to the right or left, their direction of travel must be reversed. Accordingly, at both ends of the rack 106 is provided a post 107 (only one being shown) above which is pivotally mounted a spring biased dog 108 which lies in the path of the end of the connecting member 93. When the end of this member strikes the dog 108, the member 93 slides in its bearing 94, thus to disengage one of the pinions 87 or 88 from the gear 96 or 97, and engage it with the other. This causes the saws to oscillate about the shaft 59. The spring pressed dog prevents sudden and harsh meshing of the gears.

As the cutters and saws remove the coal, it falls to the floor in the path of a pair of conveyors 109 and 111. As seen, these conveyors comprise outer flights 110 running forwardly in open sided troughs 115, and turn at the front to travel rearwardly with the load, carrying the same in a trough 112 extending from front to rear of the machine. At the rear of the machine the coal is delivered on to a supplementary conveyor 125 to be carried out of the mine. The conveyors 109 and 111 may be of the usual chain type running on idler sprockets 113.

In order to drive the conveyors 109 and 111 from the motor 26, there is provided a sprocket 114 loosely mounted on the shaft 22. The sprocket 114 is provided on either side with one element 116 of a ratchet clutch, and the other elements 117 and 118 thereof are slidably splined to the shaft 22. Springs 119 and 121 bias the elements into engagement with element 116. The teeth of this clutch are so inclined that they engage only when the machine is moving forward, that is, when the tracks 12 are being driven by the motor 26 through gear 23 and pinion 24. When the machine is travelling backward, the ratchets slip and sprocket 114 is not rotated.

At the rear of the machine are provided a pair of vertical shafts 122 and 123, carrying at their top ends gears 124 and 126 in engagement with pinions 127, which latter are mounted on a shaft 129. The shaft 129 has keyed thereto a sprocket 131 which is connected by a chain 132 to the sprocket 114. At their lower ends the shafts 122 and 123 have keyed thereto sprockets 133 and 134 which are in mesh with the conveyor chains. Idler sprockets 136 and 137 are provided as shown.

A shield 138 is mounted on the post 59 and has an opening 139 therein through which the operator may see to the rear. The overhanging rear portion of the machine is further supported by tie rods 141.

Referring to Figs. 6 and 7, the entire machine may be raised or lowered, or adjusted as to height, by raising and lowering the main frame 11 with respect to the frame for the caterpillar drive 12,

which is shown in Fig. 6 at 142, and on either side of which are guide elements 143 secured to the frame 11, as shown in Fig. 7. A rigid yoke 144 connects the side frame members 142 and has intermediate its ends an opening 145 having a rounded bottom within which seats the spherical end 146 of a jack screw 147. The jack screw 147 is threaded through a transverse beam 148, forming a part of the main frame 11, and a hand wheel 149 is keyed to the upper end of the jack screw. The main frame 11 of the machine is thus suspended from the caterpillar frame 142 through the jack screw 147. It will be seen that when the hand wheel 149 is screwed down on the jack screw it will lift the machine, and when it is backed off the jack screw 147 the machine will be lowered with respect to the caterpillar drive frame. Similar adjustment 151 is provided on the opposite side of the machine and need not be described.

Electric current for operating the motors 26, 62 and 63 is conducted to the machine through a cable 152, which may be wound on a reel 153 mounted in suitable bearings 154. The reel 153 provides means for accommodating the machine to the distance from the source of power, the reel being rotated when necessary by any suitable means, not shown. The conductors inside the cable 152 terminate in slip rings 156. Brushes 157 bear on the slip rings 156, and are connected by suitable conductors through a cable 158 to the motors.

In the operation of the machine, the rapid cutting of coal creates a great amount of dust, and water may necessarily have to be sprayed on the face being mined. I show in Fig. 8 a water hose 159 which is wound on a drum 161 mounted in suitable bearings 162 on the frame of the machine. The drum 161 is preferably made hollow with the end 163 of the hose connected to the interior of the drum. Water may be taken out of the drum through a swivel connection 164 and delivered through a hose 166 to the front of the machine, where it terminates in a spray 167 (see Fig. 1).

Referring to Fig. 10, which is a diagrammatic sectional showing of a coal mine, the method of use of my improved machines will be clearly understood. In Fig. 10 I show a heading 168 and companion air courses 169 and 170 on opposite sides of the heading. The intervening pillars 171 and 172 between the heading and its companion air courses should each be about one-half the width of the heading and the air courses. For example, if the headings and air courses are each 10 feet across, the intervening pillars should be 5 feet. In each of the air courses 169 and 170, and in the heading 168, I show one of my improved machines 173. Coal being mined is carried out of the mine by the supplementary conveyor 125 associated with the machine in the heading 168. The supplementary conveyors 125 associated with the machines in the air courses 169 and 170 do not necessarily extend to the outside of the mine, but may deliver their coal to the conveyor 125 in the heading 168 by means of cross conveyors 174, indicated diagrammatically in the drawings, which go through suitable ventilating openings 176 in the intervening pillars 171 and 172. As is well understood, the openings 176 are constructed at suitable intervals to insure the proper ventilation of the workings.

The machines 173 being driven forward constantly, it will be seen that the cutters 77, instead of travelling in a true arc, travel in a curved path,

which is a resultant of their oscillatory motion plus the forward motion of the machine as a whole. The dotted lines 178 indicate the nature of the cut being made. In its forward advance, the machine is guided by the guides 14, and its working height is adjusted by means of the adjusting wheels 149 and jack screws 147, as already explained. As the material is dislodged by the cutters 77, it is moved rearwardly by the conveyor 109 and delivered to the supplementary conveyor 125 which carries it out of the mine. The supplementary conveyor shown is intended to be of standard construction, which may be lengthened from time to time to accommodate the advance of the machine. As this construction is well understood, its detail description is not necessary at this time.

From the foregoing it will be apparent that I have devised an improved mining machine which is adapted for the continuous mining of coal, and particularly in the driving of headings and air courses.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. A mining machine comprising a main frame, a secondary frame mounted to oscillate on the main frame, rotary circular saws carried by the secondary frame with their faces substantially parallel to the mine face, means for simultaneously driving the main frame, the saws and for oscillating the secondary frame, a conveyor trough mounted intermediate the sides and extending rearwardly of the machine, and conveyor flights adapted to engage the material mined by the cutters along the sides of the machine and to move it in the trough to the rear of the machine.

45 2. A mining machine comprising a main frame, a secondary frame mounted to oscillate on the main frame in a horizontal plane, rotary cutters carried by the secondary frame, driving means for the cutters and for oscillating the secondary frame, a conveyor trough mounted intermediate the sides and extending rearwardly of the machine, and conveyor flights moving forwardly of the machine around the perimeter thereof and joining to move rearwardly of the machine in the conveyor trough whereby to engage the dislodged material and move it in the conveyor trough to the rear of the machine.

3. A mining machine comprising a main frame, a secondary frame mounted to oscillate on the main frame in a horizontal plane, rotary cutters carried by the secondary frame, driving means for the cutters and for oscillating the secondary frame, a conveyor trough mounted intermediate the sides and extending rearwardly of the machine, and conveyor flights moving forwardly of the machine around the perimeter thereof and joining to move rearwardly of the machine in the conveyor trough whereby to engage the dislodged material and move it in the conveyor trough to the rear of the machine, and a supplemental conveyor to remove the material from the mine.

4. In a mining machine, the combination with a main supporting frame, of a supplemental frame mounted for horizontal oscillatory move-

ment about a vertical axis in front of a vertical mine face, rotary cutters mounted on the supplemental frame to engage and dislodge material from the face and in a cut substantially parallel to the face, power means for driving the cutters, reversing gear means interposed between the power means and the cutters to effect oscillatory movement thereof, and means to advance the machine toward the mine face during the oscillatory movement to effect a cutting action which is a resultant of their oscillatory motion plus the forward motion of the machine as a whole during both directions of the oscillatory movement.

5. In a mining machine, the combination with a main supporting frame, of a supplemental frame mounted for horizontal oscillatory movement about a vertical axis in front of a vertical mine face, rotary shafts extending normal to the face mounted on the supplemental frame, circular saws mounted on the ends of the shafts to engage and dislodge material from the face, power means for driving the saws, reversing gear means interposed between the power means and the cutters to effect oscillatory movement thereof, endless track supports for the main frame, power means for driving the endless tracks during operation of the saws, and reversing gear means interposed between the power means and the track supports for effecting movement of the machine selectively in a forward or rearward direction.

6. A mining machine as set forth in claim 5, in combination with adjustable lateral guiding means disposed to engage the walls of the mine

workings, and means to vary the angular position of the main frame with respect to the endless track supports.

7. In a mining machine for operation before a vertical mine face, the combination with supporting frame work, of coal cutting mechanism comprising saws mounted for horizontal oscillatory movement relative thereto and a cutting action substantially parallel to the mine face, means for operating said coal cutting mechanism to cut coal in both directions of its oscillatory movement, means to advance the machine during the cutting operation to effect a cut which is a resultant of the oscillatory movement of the saws plus the forward motion of the machine as a whole, and a conveyor for transferring dislodged material toward the rear of the machine.

8. In a mining machine, the combination with supporting frame work, of a supplemental frame mounted for horizontal oscillatory movement about a vertical axis and before an upright mine face, coal cutting mechanism comprising a plurality of cutters mounted on the supplemental frame to oscillate therewith and adapted to cut coal in both directions of their oscillatory movement, power means for driving the cutters, reversing gear means interposed between the power means and the cutters to effect oscillatory movement thereof, and means to advance the machine toward the mine face during the oscillatory movement to effect a cutting action which is a resultant of the oscillatory motion plus the forward motion of the machine as a whole during both directions of the oscillatory movement.

ERSKINE RAMSAY.
